Primary Examiner — Kevin Rudzinski(74) *Attorney, Agent, or Firm* — James L. Young; Westman, Champlin & Koehler, P.A.(57) **CLAIM**

The ornamental design for a hand-held container, as shown and described.

DESCRIPTION

FIG. 1 is a perspective view of the hand-held container, as viewed from the top, rear, and right side thereof;

FIG. 2 is a top plan view of the hand-held container of FIG. 1; FIG. 3 is a front elevational view of the hand-held container of FIG. 1;

FIG. 4 is a right side view of the hand-held container of FIG. 1;

FIG. 5 is a left side view of the hand-held container of FIG. 1; FIG. 6 is a rear elevational view of the hand-held container of FIG. 1; and,

FIG. 7 is a bottom plan view of the hand-held container of FIG. 1.

The broken lines illustrating portions of the hand-held container in the Figures form no part of the claimed design.
